UNITED STATES PATENT OFFICE.

THOMAS E. PECK AND FRANK W. HARRISON, OF SIOUX CITY, IOWA.

STOCK OILER.

Application filed April 10, 1926. Serial No. 101,109.

Our invention relates to a stock oiler of the type disclosed in our issued Patent No. 1,566,558, issued December 22, 1925, and it is our object to improve upon the construction of such an oiler by simplifying such structure.

More specifically, it is our object to provide an oiler comprising a gate adapted to be mounted in a fence or the like, means for spraying oil from above said gate, and means for directing the spray of oil to the side of the gate away from the direction in which the gate swings, such shifting of the spray being accomplished in the present invention by the use of a single nozzle, the position of which is changed by the swinging of the gate.

With these and other objects in view, our invention consists in the construction, arrangement and combination of the various parts of our device, whereby the objects contemplated are attained, as hereinafter more fully set forth, pointed out in our claims and illustrated in the accompanying drawings, 25 in which:

Fig. 1 is a side elevation of the oiler.

Fig. 2 is an end elevation of the same.

Fig. 3 is a plan view of the same.

Fig. 4 is a detail sectional view, taken on the line 4—4 of Fig. 1.

Fig. 5 is a detail sectional view, taken on the line 5—5 of Fig. 2, and

Fig. 6 is a detail sectional view, taken on the line 6—6 of Fig. 1.

Although we have shown in the accompanying drawings an integral structure embodying a gateway and a gate, it will be understood that the invention may be prepared in the form of a gate adapted to be mounted in any sort of gateway which may be provided.

The gateway is shown generally at 10, and has the side uprights, 11 and 12, and the upper cross piece, 13. To the upright, 11, is secured a bracket, 14, having a bearing, 15, which, together with the bearing 16, secured to the upright, 12, journals a shaft, 17. The gate, 18, which may be of sheet metal or any other construction is hung from the shaft, 17, and secured thereto as by the loops, 19. It will thus be seen that swinging of the gate will cause the shaft, 17, to oscillate.

The bracket, 14, has a socket, 20, which receives the pump cylinder, 21. A cap, 22, bolted to the socket, 20, secures the cylinder, 21, in place.

The cylinder, 21, is fed with oil from a tank, 22^a, which has been shown in Fig. 1 and omitted from the rest of the figures.

The piston of the pump, which is not shown, is actuated by the piston rod, 23, extending through a packing gland, 24, in the lower end of the pump. A crank arm, 25, is secured in the end of the shaft, 17, and has a bifurcated portion, 26, receiving the end of a pitman, 27, which is linked pivotally thereto and to the rod, 23, as shown.

The oil is delivered from the pump cylinder, 21, through a goose neck, 28^a, which extends around the shaft, 17, to a pipe, 28. The pipe, 28, has a vertical portion, 29, provided at its lower end with a flange, 30. A packing nut, 31, engages the flange, 30, against the end of the goose neck, 28^a, and a packing ring, 33, is interposed to prevent leakage of the oil. This construction allows the pipe, 28, to swing laterally.

A check valve, 32, prevents flow of oil back into the tank, 22, and a check valve, 32^a, prevents flow of oil rearwardly from the pipe, 28, to the pump cylinder.

The other end of the pipe, 28, as at 34, forms a nozzle which extends downwardly through a transverse slot, 35, in the top cross piece, 13, of the gateway. The nozzle may swing laterally of the gateway within the slot, 35. A nut, 36, supports the free end of the pipe, 28, and slidably bears against the upper surface of the cross member, 13.

Any sort of flexible connection may be employed as a substitute for the construction shown in Fig. 5, and the nozzle instead of swinging bodily laterally may be allowed, for instance, to tilt laterally around a horizontal instead of a vertical axis, and yet accomplish the same result, namely, directing the oil discharge from the nozzle to one side or the other of the gate.

In order to control the swing of the nozzle in either manner above mentioned, we provide a lever co-acting with the lower end of the nozzle and actuated to swing the lower end to one side or the other of the gate. The lever is shown at 37 and is pivoted to the under side of the cross piece at 38. The free end of the lever has an opening, not shown, which loosely receives the nozzle, 34.

Intermediate the ends of the lever is a depression, 39, which receives a stud, 40, secured in the shaft, 17, and projecting upwardly. (See Fig. 6.) The lever is pro-

vided with a ring, 41, surrounding the depression, 39, so as to prevent disengagement of the stud, 40, from the lever.

It will now be seen that as the gate is 5 swung in one direction the stud, 40, will move in the other direction and carry the lever with it. The lever, swinging around a vertical axis in a direction reverse to that of the swing of the gate will move the nozzle 10 to one side or the other of the gate.

The action of the stud, 40, in moving the lever, 37, is very rapid and takes place during the commencement of the swing of the gate. On the other hand, the action of the 15 pump increases as the gate is swung outwardly, and at the beginning of the swing there is no pump action whatever. This is due to the crank arm operating means, the arm, 25, being on dead center with the pit- 20 man, 27, when the gate is depending in its normal vertical position. (See Fig. 3.) As the angle of the arm, 25, changes during its swing the relative movement of the piston rod, 23, will be increased.

25 The parts are so arranged that the gate will have swung sufficiently to move the nozzle, 34, to either of its extreme positions where the stream of oil will not be interfered with by the shaft, 17, before the nozzle 30 begins to eject the oil. The slight play in the pivotal connection between the arm, 25, the pintle, 27, and the piston rod, 23, aids in accomplishing this result.

The length of the lever, 37, beyond the 35 depression, 39, is sufficient to magnify the movement imparted to the lever by the stud, 40, several times, and consequently the engagement of the stud, 40, with the depression, 38, need occupy only a small portion 40 of the swing thereof. As the stud moves to one side it will slip out of the depression and slide within the ring, 41, which prevents binding of the stud against the lever as it swings back to reenter the depression, 38.

45 Some changes may be made in the construction and arrangement of the parts of our invention without departing from the real spirit and purpose of our invention, and it is our intention to cover by our claims 50 any modified forms of structure or use of mechanical equivalents which may be reasonably included within their scope.

We claim as our invention:

1. In an oiler, a gateway, a gate hinged 55 therein at its upper extremity, a nozzle above the gate, means actuated by the swing-

ing of the gate for delivering fluid to said nozzle, and means operated by the swinging of the gate to move said nozzle to one side of the gate in a direction reverse to the 60 direction of swing of the gate.

2. In an oiler, a gateway, a gate hinged therein at its upper extremity, a nozzle above the gate, and means operated by the swinging of the gate to move said nozzle to one 65 side of the gate in a direction reverse to the direction of swing of the gate.

3. In an oiler, a gateway, a gate hinged therein on a horizontal axis near its upper edge, a nozzle above the gate, and means 70 operated by the swinging of the gate to direct said nozzle to a position to discharge on the side of the gate away from the direction of swing thereof.

4. In an oiler, a gateway, a gate hinged 75 therein at its upper extremity, a nozzle above the gate, a pump actuated by the swinging of the gate for pumping oil to the nozzle, said nozzle being joined to said pump by a connection allowing movement 80 of the nozzle laterally of the gate, and means actuated by the swinging of the gate to move said nozzle to a position directed to discharge over the gate on the side away from the direction of swing of the gate. 85

5. In an oiler, a gateway, a gate hinged therein at its upper extremity, a nozzle above the gate, a pump actuated by the swinging of the gate for pumping oil to the nozzle, said nozzle being joined to said 90 pump by a pipe having a swinging connection with the pump, and means actuated by the swinging of the gate to move said nozzle to one side of the gate in a direction reverse to that of the swing of the gate. 95

6. In an oiler, a gateway, a gate hinged therein at its upper extremity, a nozzle above the gate, and means operated by the swinging of the gate to direct said nozzle to a position to discharge on the side of the gate 100 away from the direction of swing thereof, said means comprising a lever pivoted to the gateway above the gate, the free end of said lever engaging the nozzle, and a projecting member on the gate engaging said 105 lever.

Signed at Sioux City, in the county of Woodbury and State of Iowa, this 30th day of March, 1926.

THOMAS E. PECK.
